SNAGPROOF DRAG

Morton Leslie Thompson, East Moline, Ill.

Application July 18, 1947, Serial No. 761,914

14 Claims. (Cl. 294—66)

1

The present invention relates to drags or grapples used for the recovery of the bodies of persons from large bodies of water, such as lakes, ponds, or rivers or for the recovery of other objects.

The usual device for recovering bodies from deep water is provided with a plurality of hooks which are arranged at various angles, on the theory that by chance one or more of the hooks may become entangled with the clothing on the body or possibly some appendage of the body may be caught by the hook. Since these hooks must be open toward the direction in which they are being dragged these hooks easily become fouled or entangled in any underbrush, logs and other sunken objects. Also the lines to these grapple hooks are attached to an eye at the front of the hooks so that it is very hard to dislodge them when they become caught on sunken objects. The present invention is a considerable departure from these prior devices and one of its salient features is the provision of a device which may be disentangled from sunken objects by reversing the direction of pull on the device.

Accordingly, the primary object of the invention is to provide an improved device for the purposes mentioned which may be readily disentangled from fixed objects.

Another object is to provide a snag-proof drag adapted to be pulled along the bottom of a lake or stream bed from a point above the water for recovering bodies of persons and which drag may be tilted automatically to disengage it from fixed objects by reversing the direction of pull. The device forming the object of this invention is relatively snag-proof in the sense that it is easily and quickly released from the snag by a mere reversal of the direction of pull.

Another important object is to provide a drag of the type characterized which is of simple construction, durable and may be manufactured at low cost from readily available parts.

Other and further objects will become apparent from the following description when considered in connection with the accompanying drawings illustrating an embodiment of the invention, and in which,

Fig. 1 is a perspective view of the device which forms a preferred embodiment of the invention;

Fig. 2 is a side elevation, the full lines showing the device when towed to the right and the dotted lines showing the position assumed by the device when the direction of pull on the rope is reversed;

Fig. 3 is a perspective view of an alternative embodiment of the invention;

2

Fig. 4 is a side elevation showing a portion of one of the divergent arms of the frame and the associated pivotally mounted prongs;

Fig. 5 is a top or plan view of the portion of the device shown in Fig. 4;

Fig. 6 is a end view, partially in section and partially in elevation, of the portion of the device shown in Fig. 4;

Fig. 7 is a detail view of the yoke member and mounting therefor; and

Fig. 8 is a partial detail elevational view of Fig. 3.

In the drawing in which like characters of reference designate like or similar parts throughout the several views, the embodiment of the invention illustrated in Figs. 1 and 2 includes a substantially triangular frame 5 formed of two divergent members 7 and 9. The members are preferably made of metal tubes secured together in a suitable manner such as by welding or brazing to form an open-ended V. The member 7 is adapted to serve as a skid bar when the device is dragged along the bottom of a body or stream of water.

The member 9 constituting the other side of the V-shaped frame is attached to the skid bar member 7 in such a way that when the skid bar member 7 is horizontal as shown in the drawing the member 9 will be inclined upwardly in the direction in which the device is adapted to be dragged through the water to recover the body of a person. To the upper end of the member 9 are fixed depending spaced plates 10 which constitute a hinge to which a depending gate bar 11 is pivotally connected by means of a pin 12. The plates 10 may be secured to the member 9 in any suitable manner as by means of welding or brazing. When the frame of the drag is disposed in the vertical position as shown in the drawing, the gate bar 11 is adapted to hang straight downwardly under the action of gravity so that the lower end of the gate bar is disposed just above the front end of the skid bar member 7.

The skid bar member 7 has attached to its front end, as by welding or brazing, a guide prong 17 which extends rearwardly and upwardly towards the member 9, the angle and the length of the guide prong 17 being such that it terminates just under the lower end of the gate bar 11 when the latter hangs vertically. The guide prong 17 together with the skid bar member 7 forms a wedge for entering beneath the body of a person for lifting the latter into the drag. A plurality of parallel prongs 19 are suitably secured to the skid bar member 7 and are inclined upwardly and rearwardly therefrom, each of the said

prongs 19 forming an angle with the skid bar member somewhat larger than the angle between the guide prong 17 and the skid bar member. The prongs 19 all lie in the plane with the guide prong 17 and the plane of the triangular frame of the drag. Behind the rearmost prong 19 a yoke-like member 21 is suitably fixed to the skid bar member 7, the legs of the yoke-like member being in the plane of the triangular frame and both ends of said legs being suitably attached to the skid bar member 7. The foremost leg of the yoke member 21 is parallel to the prongs 19. The bight of a V-shaped prong member 22 is welded or brazed to the skid bar member 7 at the junction of the latter with the rear leg of the yoke-like member 21. The two legs of the V-shaped prong member 22 are inclined upwardly, rearwardly and laterally of the skid bar member 7.

The primary purpose of this V-shaped prong member 22 is to engage the clothing or the appendages of the body of the person or other objects being recovered from the water and to prevent the body or objects from slipping transversely of the plane of the drag.

A plurality of parallel prongs 23 are welded or brazed to the front side of the depending gate bar 11 and are inclined downwardly and forwardly of the frame of the drag. These prongs lie in the plane of the frame of the drag. The primary purpose of these prongs is to cooperate with the prongs 19 on the skid bar member 7 for engaging and preventing a body or object from sliding transversely of the drag.

One of the salient features of the present invention resides in the method of attaching the rope or lines by which the drag is pulled through the water. To this end, the side frame member 9 constitutes the draw bar for the frame and is adapted to receive a device to which the rope or lines may be attached. In the form shown in the drawing, a ring 25 is adapted to slide up and down along the full length of the member 9. A rope or line 26 is attached to the ring 25 for the purpose of dragging the frame through the water. When the drag is being pulled forward, the rope or line 26 will be inclined upwardly and to the right as shown because the drag is usually pulled from a boat which, of course, is above and in front of the drag since it is intended that the drag slide along on the bottom of the stream or lake.

In the operation of the above described embodiment, the drag is usually used in pairs, being partially suspended by ropes from the opposite side of a boat. It will be readily understood that sufficient tension must be maintained on the rope 26 so that the plane of the frame of the drag will be held in a vertical position with the member 7 on the bottom serving as the skid element when the drag is being pulled forward. When the pulling thrust is applied toward the right in the drawings, the ring 25 will slide to the upper forward end of the member 9. Since the drag will be sliding on the bottom of the lake or stream, the forward thrust on the drag will tend to tip the forward end of the drag downwardly. In the event the drag engages a body, the guide prong 17 will tend to raise the latter up over the skid bar member 7. At the same time the swinging gate bar 11 will swing rearwardly and permit the body to enter between the skid bar member 7 and the member 9. The weight of the gate bar 11 will cause it to tend to swing to the vertical position to hold the body or other object securely in the drag.

5 In the event that the drag becomes engaged under a fixed object in the water, the drag may be released therefrom by reversing the direction of pull on the rope 26. When the pull on the rope is applied to the left of the drag as shown in the drawing, the ring 25 will slide to the rear of the member 9 as shown in broken lines in Fig. 2 and the pull on the rope 26 will change the point through which the pulling thrust is applied to the frame of the drag.

10 This will result in a change in the resultant turning moment acting on the drag so that the rear end of the drag will be raised regardless of whether or not the front end of the drag is caught on a fixed object. As a result, the drag will turn about a point forward of its center so that a downward force will be applied to the front end of the drag.

15 It will be noted that the guide prong 17 makes a very small angle with the skid bar member 7 so that when the rear end of the drag is raised and pulled backward the tendency for the rear end of the guide prong to become or remain engaged with a fixed object will be minimized.

20 A second embodiment of the invention for effecting the disengaging of the drag from objects in the body of water is shown in Fig. 3 to 7, inclusive, in which the depending gate bar 11 is eliminated. The parts common to both described embodiments of the invention are designated by the same reference characters as employed in Figs. 1 and 2. Referring to Fig. 3 showing a perspective view of this embodiment of the invention, the frame members 7 and 9 are suitably secured together to form the substantially triangular frame 5 in the manner described in the description of the previous embodiment. Secured at each end to the divergent frame member 9 and spaced therefrom is a draw bar 31, disposed with its axis parallel to the axis of the divergent member 9 and extending substantially along the full length of member 9. The ring 25 to which the tow rope or line 26 is secured is mounted on the draw bar 31 and adapted to slide up and down the 30 full length of the draw bar 31 along member 9 so that tension on the tow rope 26 will maintain the plane of the drag frame 5 in a vertical position when towed.

25 A plurality of substantially U-shaped prongs or teeth 33, shown in detail in Figs. 4 to 6, are pivotally secured to the mutually adjacent surfaces of the divergent members 7 and 9 to engage and hold the clothing or the appendages of the body of the person or other objects entering the opening defined by the members 7 and 9. These prongs or teeth 33 are formed preferably of metal rods shaped to provide substantially parallel arms 34 and 35 extending perpendicularly to the portion 36 forming the pivotal axis of the prongs, 30 the arms 34 and 35 having mutually divergent sheared points 37 and 38 formed on the ends thereof. Mounting bars 40 and 41 having semi-circular transverse recesses 42 along one surface thereof are suitably secured to the mutually adjacent surfaces of the divergent members 7 and 9 respectively, as by welding or brazing, with the recesses 42 disposed toward the surface to which the mounting bar is secured, the recesses 42 providing mounting sockets for the portions 36 of 35 the prongs 33 to secure the prongs to the divergent members 7 and 9 for pivotal movement on mutually parallel transverse axes perpendicular to the axes of the respective divergent members 7 and 9. Positioning plates 43 and 44 having 40 spaced slots 45 and 46 therein adapted to receive

the arms 34 and 35, respectively, of the prong members 33 therethrough are disposed along the mutually adjacent surfaces of the respective members 7 and 9, to position the prongs 33 pivoted to the respective divergent frame members in respective parallel planes. The adjacent ends of the positioning plates 43, 44 near the junction of the members 7 and 9 abut against each other with a flange 47 formed at the end of the plate 43 overlapping the end 48 of plate 44. The flange 47 and the end 48 may be secured together by welding or any other appropriate means.

Near the front end of divergent member 9, a yoke member 50 is provided, comprising lever arms 51, 52 and cross members 53, 54 connected therebetween. The yoke member 50 is pivotally mounted on the mounting bar 41 by means of a pin 55 extending between the lever arms 51, 52 and through a suitable opening in the bar 41 to position the upper ends of the lever arms, 51, 52 in the path of the ring 25 to which the tow line 26 is secured. A cross member 56 is welded across lever arms 51, 52 and serves as a stop for limiting the pivotal movement of the yoke 50. The lever arms 51, 52 engage the plate 44 and urge the latter axially toward the junction of the divergent members 7 and 9 when the tow ring 25 is abutting the lever arms 51, 52.

In the operation of the above embodiment of the invention, when the pulling thrust is applied to the tow line 26, in a direction toward the right of the drawing, the ring 25 will be drawn along the draw bar 31 to the position shown in Fig. 3, engaging the lever arms 51, 52 and camming them clockwise about the axis of pin 55. The cross member 56, disposed between the lever arms 51, 52 opposite the pivot pin 55, serves as a stop for the yoke member 50 when the top of the latter is moved to the right in Figure 3 and member 56 engages the underside of the positioning plate 44. The lever arms 51 and 52 engage the end of the positioning plate 44 to force the latter toward the junction of the divergent members 7 and 9. By reason of engagement between the end 48 and the flange 47 the positioning plate 43 will also be moved toward the junction of members 7 and 9 and thereby rock the pivoted prongs 33 extending through the slots 45, 46 of the plates 43, 44 respectively, inwardly from the front ends of the members 7 and 9 to engage and retain objects entering through the opening formed by the members 7 and 9.

In the event the drag becomes engaged under a fixed object in the water, the drag may be released therefrom by reversing the direction of pull on the tow rope 26. When the direction of pull is reversed, the ring 25 will slide to the rear of the member 9 along the draw bar 31 to a position near the junction of members 7 and 9, releasing the yoke member 50 to permit it to rotate counterclockwise about the pivot pin 55, and permit the positioning plates 43, 44 to move axially toward the respective front ends of the divergent frame members 7 and 9 and cam the prongs 33 to positions at right angles to the respective frame members or to forwardly inclined positions to release the snag, at the same time raising the rear end of the drag in a manner similar to that described in the previous modification.

From the above description, it will be readily apparent that the present invention provides a novel device for recovering bodies of persons from lakes, ponds, or streams. Because of the novel means for attaching the tow ropes or lines to the drag, the latter may be readily disengaged from

any fixed underwater obstruction by merely reversing the direction of pull.

Although the invention has been described in considerable detail, it will be apparent to those skilled in the art that many variations are possible without departing from the inventive concept, except as limited by the appended claims.

What is claimed is:

1. A drag for recovering bodies of persons from a body of water, such as a lake, pond, or stream, comprising a frame including forwardly diverging members defining an opening at their divergent front ends, means pivoted to the forward end of one of said members for closing said opening, means carried by the other of said members for engaging and holding a body to be recovered, and means operably associated with said frame and movable relative thereto through which a pulling thrust may be applied to said frame at different points.
2. A drag for recovering bodies of persons from a body of water such as a lake, pond, or stream, comprising a frame having two divergent members secured together to constitute a V-formation, a third member pivoted to one end of said members and forming a closure for said V-formation, and means slidable on one of said members to which a rope or the like may be attached for operating the drag.
3. A drag for recovering bodies of persons from a body of water, such as a lake, pond or stream, comprising a frame having two divergent members secured together to constitute a V-formation, a third member pivoted to one end of one of said members and forming a closure for said V-formation, said frame being adapted to be dragged along the bottom of a body of water with the plane of said frame disposed vertically and with one of said members serving as a skid element, and means having a slidable connection with said frame for applying a pulling thrust to said frame at different points thereof.
4. A drag for recovering bodies of persons from a body of water such as a lake, pond or stream, comprising a frame including forwardly divergent members defining an opening by their divergent front ends for receiving a body to be recovered, said frame adapted to be dragged along the bottom of a body of water with the plane of said frame disposed vertically and with one of said members serving as a skid element, a third member pivoted to the forward end of the other of said members and forming a closure for the divergent open end of said frame, and means operably associated with said frame and movable relative thereto through which a pulling thrust may be applied to said frame at different points.
5. A device as described in claim 6 in which the member serving as a skid element is provided with prongs inclined from the open end of said frame toward the rear thereof and said third member is provided on its front side with parallel prongs inclined downwardly toward the front of said frame.
6. A device as defined in claim 4 in which the frame member serving as the skid element is provided with parallel prongs inclined upwardly and rearwardly and a yoke-like member in which the plane of the yoke member is substantially parallel to said prongs with the legs of said yoke-like member inclined transversely of the plane of said frame.
7. A drag for recovering bodies of persons from a body of water such as a lake, pond or stream, comprising forwardly divergent members de-

7
fining an opening by their divergent front ends, said frame being adapted to be dragged along a body of water with the plane of said frame disposed vertically and with one of said members serving as a skid element, a third member pivoted to the forward end of said other frame member and forming a closure for said opening, said third member normally hanging vertically under the action of gravity, and means operably associated with said frame and movable relative thereto through which a pulling thrust may be applied to said frame at different points to alter the effect of the thrust on the resultant turning moment acting on said frame as a result of the pulling thrust.

8. A drag for recovering bodies of persons from a body of water such as a lake, pond or stream, comprising a frame having an open end for receiving a body or object to be recovered, means operatively associated with said frame and movable relative thereto through which a pulling thrust may be applied to said frame at different points to alter the effect of the thrust on the resulting turning moment acting on said frame, means carried by said frame for engaging and holding a body to be recovered, and means actuated by the means applying the pulling thrust to said frame for alteration permitting the position of said engaging and holding means to render the same ineffective for holding bodies when the direction of said pulling thrust is altered.

9. A drag for recovering bodies of persons from a body of water such as a lake, pond or stream, comprising a frame including forwardly diverging members defining an opening at their divergent front ends for receiving a body to be recovered, means operatively associated with said frame and movable relative thereto through which a pulling thrust may be applied to said frame at different points to alter the effect of the thrust on the turning moment acting on said frame, means carried by the forwardly diverging members for engaging and holding the body to be recovered, and means actuated by the means applying the pulling thrust to said frame for altering the position of said engaging and holding means to render the same ineffective for engaging and holding bodies when the direction of said pulling thrust is altered.

10. A drag for recovering bodies of persons from a body of water such as a lake, pond or stream, comprising a frame having two divergent members secured together to constitute a V-formation, said frame being adapted to be dragged along the bottom of a body of water with the plane of said frame disposed vertically and with one of said members operative as a skid element, means having a slidable connection with said frame for applying a pulling thrust to said frame at different points thereof, means carried by the mutually adjacent surfaces of said divergent members for engaging and holding a body entering said V-formation and means actuated by the means applying the pulling thrust to said frame for permitting the alteration of the position of said engaging and holding means relative to said frame to render the same ineffective to engage and hold bodies when the direction of the pulling thrust is substantially reversed.

11. A drag for recovering bodies of persons from a body of water such as a lake, pond or stream, comprising a frame having forwardly divergent members defining an opening by their divergent front ends for receiving a body to be

recovered, said divergent members being oriented to render the plane of said frame disposed vertically with one of said members serving as a skid element when a pulling thrust is applied to the other of said members to drag the frame along the bottom of a body of water, means having a slidable connection with the upwardly disposed divergent member for applying the pulling thrust to said member at different points thereof, means pivotally secured to the mutually adjacent portions of said divergent members and inclined rearwardly toward the junction of said divergent members for engaging and holding the body to be recovered, and means engaging said pivotally secured means and actuated by the means applying the pulling thrust for permitting rocking or pivotal movement of said pivotally secured means to render the same ineffective to engage and hold bodies when the direction of the pulling thrust is substantially reversed.

12. A drag for recovering bodies of persons from a body of water such as a lake, pond or stream, comprising a frame having forwardly divergent members defining an opening by their divergent front ends for receiving a body to be recovered, said divergent members being oriented to render the plane of said frame disposed vertically with one of said divergent members serving as a skid element when a pulling thrust is applied to the other of said members to drag the frame through a body of water, means having a slidable connection with the upwardly disposed divergent member for applying the pulling thrust to said member at different points thereof, a plurality of mutually parallel prongs pivoted to the mutually adjacent portions of said divergent members, interconnected means associated with each of said divergent members slideable on axes parallel to the axis of its associated divergent member and engaging each of said prongs, and means positioning said interconnected means to incline said prongs rearwardly toward the junction of said divergent members when said means applying the pulling thrust is at one end of said slidable connection, said positioning means permitting said interconnecting means to incline said prongs forwardly from the junction of said divergent members when said means applying the pulling thrust is positioned at other than said end of said slidable connection.

13. A drag for recovering bodies of persons from a body of water such as a lake, pond or stream, comprising a frame having forwardly divergent members defining an opening by their divergent front ends for receiving a body to be recovered, means operatively associated with said frame and movable relative thereto through which a pulling thrust may be applied to said frame at different points to alter the effect of the thrust on the resulting turning moment acting on said frame, means carried by said frame for engaging and holding a body to be recovered, and means actuated by the means applying the pulling thrust to said frame for positioning said means for engaging and holding a body in one position when the pulling thrust is applied in one direction and permitting the alteration of the position of said engaging holding means to render the same ineffective for holding bodies when the direction of said pulling thrust is altered.

14. A drag for recovering bodies of persons from a body of water such as a lake, pond or stream, comprising a frame having an open end for receiving a body or object to be recovered,
